UNITED STATES PATENT OFFICE.

DENNIS W. MORRISON, OF INDIANA HARBOR, INDIANA.

LATTICE-TRUSS.

1,345,501.

Specification of Letters Patent.

Patented July 6, 1920.

Application filed February 1, 1917. Serial No. 145,963.

To all whom it may concern.

Be it known that I, DENNIS W. MORRISON, a citizen of the United States, and a resident of the city of Indiana Harbor, in the county 5 of Lake and State of Indiana, have invented certain new and useful Improvements in Lattice-Trusses; and I do hereby declare that the following is a full, clear, and exact description of the same, reference being had 10 to the accompanying drawings, and to the numerals of reference marked thereon, which form a part of this specification.

This invention relates to an improved form of roof or bridge truss wherein the use 15 of large heavy timbers is obviated by the use of laminated planks or strips of lumber of light weight and of low cost, and wherein the lattice work is constructed with its slats substantially at right angles to one another and disposed substantially at an angle of forty-five degrees with diagonal brace bars supporting the arched portion of the truss.

It is an object of this invention to construct an improved form of truss wherein the tie-beam, braces and arch members are of laminated construction to increase the strength and reduce the cost of construction 20 of the truss.

It is also an object of this invention to provide an improved truss wherein the slats forming the lattice work of the truss are at right angles to one another and at an angle of forty-five degrees with diagonal braces 25 used in supporting the arched portion of the truss.

It is furthermore an important object of this invention to construct an improved form of lattice truss wherein the straight and curved chords are of a laminated construction, and wherein the slats forming the lattice work are disposed at an angle of forty five degrees to the laminated diagonal braces of the truss.

It is finally an object of this invention to construct a truss of great strength, simple and inexpensive in construction.

The invention (in a preferred form) is illustrated in the drawings and hereinafter 50 more fully described.

In the drawings:

Figure 1 is a side elevational view of a lattice truss embodying the principles of my invention.

Fig. 2 is a top plan view thereof.

Fig. 3 is a section taken on line 3—3 of Fig. 1.

Fig. 4 is a section taken on line 4—4 of Fig. 1.

Fig. 5 is an enlarged detail side view of 60 one end of the truss with the tie-beam and arched portion omitted.

Fig. 6 is a transverse section taken on line 6—6, of Fig. 5.

Fig. 7 is a transverse section taken on line 65 7—7 of Fig. 5.

Fig. 8 is a transverse section taken on line 8—8 of Fig. 5.

Fig. 9 is a side view in elevation of a modified form of truss used in conjunction with 70 truss rods.

As shown on the drawings:

The tie beams, straight or lower chords of the truss, are represented by the reference numeral 1, and are of laminated construction or made up of two or more strips of lumber, or other suitable material, mounted in parallel relation adjacent one another. Said tie-beams are located one 75 on each side of the lower portion of the 80 truss, and extend longitudinally for the entire length thereof to form the foundation of the truss. Mounted in the same plane with each of the tie-beams are two sets of braces or rafters 2, each of laminated construction comprising two or more thicknesses and extending diagonally upwardly toward one another to a point centrally located above the tie-beams. The upper ends of said braces form a miter joint, while the 85 lower ends are tapered as shown by the reference numeral 3, to fit into notches cut in the upper portion of each of the tie-beams 1, at a point a short distance from each end thereof, to form a scarfed joint. Braced 90 centrally against the upper surface of each of the tie-beams 1, and extending upwardly to fit beneath the upper abutting ends of the braces 2, is a laminated strut 4. Rigidly secured in notches cut in each end of 100 the upper surface of each of the tie-beams 1, and to the outside of the scarfed joints 105 therein, are laminated arched or inner curved chords 5, which are curved upwardly so that the highest or central portion thereof rests upon the abutting ends of the braces 2. From the above description it will be noted 110 that the truss comprises two side portions, each made up of the laminated members 1, 2, 4 and 5, respectively.

The lattice work of the truss which is mounted between and joins the respective side portions of the truss, comprises a plurality of slats, sway braces or lattice members 6 and 7, mounted at right angles and spaced equidistantly from one another in parallel relation. Said slats 6 and 7, are disposed at an angle of forty-five degrees with respect to the diagonal braces 2, to 10 which they are secured, as clearly shown in Figs. 1 and 5.

The side portions and the lattice work comprising the truss are rigidly secured together by nails or spikes 8, or other suitable means, the spaces between the outer ends of the tie-beams 1, having disposed therein filler blocks 9, while filler slats 10, are used where necessary to fill the spaces between the upper ends of the slats 6 and 15 7, and the inner curved chords 5. The fillers 9 and 10, are used in conjunction with the other members of the truss to afford a solid construction at points in the truss where the nails or spikes are driven in. As 20 clearly shown in Figs. 1, 5 and 9; both ends of the lattice work are made solid to act as a reinforcing means for the ends of the truss.

Mounted over the upper ends of the slats 6 and 7, and over the inner curved chords 30 5, is a laminated arch member or outer curved chord 11, of a width equal to the width of the truss, and rigidly secured to the various members of the truss by nails, spikes or other suitable fastening means.

In the modified form of the device shown 35 in Fig. 9, the construction of the truss is similar to that already described, with the exception that truss rods 12, connected by means of a turn-buckle 13, are mounted below the truss. The outer ends of said truss- 40 rods are rigidly secured to suitable bracket plates 14, secured over the ends of the tie-

beams of the truss, while struts 15, are used to brace the truss rods at points intermediate the ends thereof.

It will, of course, be understood that the various laminated members, when necessary, may be made up of a number of different lengths properly spliced together, and furthermore that solid members may be used in place of laminated members, if so desired, when practicable.

I am also aware that various other details of construction may be varied through a wide range without departing from the principles of this invention, and I therefore do not purpose limiting the patent granted otherwise than necessitated by the prior art and the claim hereto appended.

I claim as my invention:

A truss comprising in combination a straight chord, an arched member secured thereto, diagonal braces extending from the center of said member to the end portions of the chord, and lattice members in each half of the truss, the members in each half crossing each other at right angles and the adjacent diagonal brace at an angle of forty-five degrees, whereby one set of members is inclined to the chord at an angle of less than forty-five degrees and the other set is inclined to the chord at an angle of more than forty-five degrees; the lattice members in one half of the truss converging toward the lattice members in the other half, the first set of members converging upwardly and the other set converging downwardly.

In testimony whereof I have hereunto subscribed my name in the presence of two subscribing witnesses.

DENNIS W. MORRISON.
